UNITED STATES PATENT OFFICE.

EDWIN J. ARMSTRONG, OF ERIE, PENNSYLVANIA, ASSIGNOR OF ONE-HALF TO
ARTHUR C. VICARY, OF ERIE, PENNSYLVANIA.

CLOSURE FOR OIL-CHAMBER OPENINGS.

Application filed August 29, 1921. Serial No. 496,472.

To all whom it may concern:

Be it known that I, EDWIN J. ARMSTRONG, a citizen of the United States, residing at Erie, in the county of Erie and State of Pennsylvania, have invented new and useful Improvements in Closures for Oil-Chamber Openings, of which the following is a specification.

This invention is designed to form a convenient closure for receptacles for receiving oil. Where there are a great many receptacles, as with vehicles having caterpillar tracks, the convenience of supplying oil or lubricant to the great number of joints is a matter of considerable consequence. The present invention is designed to provide a means for closing such cavities in a rugged manner and in a manner that may be actuated very rapidly.

20 The invention is illustrated as being used for closing the opening to a receptacle in a roller and for operating on a caterpillar track as follows:—

Fig. 1 shows a side elevation of a caterpillar carrier with a roller mounted therein.

Fig. 2 a section on the line 2—2 in Fig. 1.

Fig. 3 a side elevation of a closure pin.

Fig. 4 an end view of the same.

Fig. 5 a side elevation, partly in section, 30 of a key for actuating the pin.

Fig. 6 an end view of the key.

Fig. 7 an enlarged section of lubricator opening with the closure pin in place and the key about to be placed in engagement 35 therewith.

Fig. 8 a similar view showing the key brought to engagement.

1 marks the roller, 2 a shaft on which the roller is mounted, 3 the walls of a caterpillar frame, 4 an axial opening in the shaft 40 leading from without the walls 3 to a point within the roller, and 5 a radial opening leading from the passage 4 to the cavity 1^a within the roller, the cavity 1^a being used 45 for retaining the lubricant for the roller.

A pin 6 conforms to the opening 4, the opening 4 being preferably straight but cylindrical and the pin 6 being also cylindrical but bent slightly as shown in Fig. 3 50 and formed of resilient material so that it may be pressed into the opening 4 and through its own resilience will retain its position therein. The pin is provided with a disc 7 supplementing the closing pin and 55 this disc 7 extends into a socket 8 in the

end of the pin. The pin is also provided with an undercut head 9 with a cut-away portion 10. The key 11 has a socket 12 with an inward projection 13 giving a contour to the opening of the socket 12 similar 60 to the contour of the head 9. The projections 13 conform to the cut-away portion 10. The key is placed over the head the disc 7 forming a stop and turned. This brings the projections 13 under portions of the 65 head in the key-way and thus locks the key with the pin so that the pin may be readily removed and the key and the pin may be conveniently returned to place although the pin may be forced to place readily from the 70 outside in any convenient manner.

The socket 8 forms a housing for the pin and as these parts are used where they are given very rough usage these pins are fully 75 protected. The lubricant openings, therefore, are conveniently and quickly closed and are not subject to the usual breakage of such devices. The disc 7 which makes a loose fit with the socket 8 operates to clean out any dirt that may be accumulated 80 in the socket 8 as the pin is withdrawn thus reducing the probability of carrying grit or dirt into the opening 4 as the pin is returned.

What I claim as new is:—

1. In a closure for oil chamber openings, the combination of a chamber wall having an opening to the chamber; and a resilient closure pin in the opening, the walls of the opening and the pin being shaped to flex 90 the pin as it is inserted to form a spring-pressed engagement between the pin and the walls of the opening, the portion of the pin within the opening being in one piece and conforming in cross section to the cross 95 sectional shape of the opening.

2. In a closure for oil chamber openings, the combination of a chamber wall having a straight chamber opening; and a resilient closure pin in said opening, said pin being 100 slightly curved and subjected to flexure as it is inserted in the opening to form a spring-pressed engagement with the walls of the opening, the portion of the pin within the opening being in one piece and conforming in cross section to the cross 105 sectional shape of the opening.

3. In a closure for oil chamber openings, the combination of a chamber wall having an opening therein with a socket at its 110

- outer end; and a resilient pin in the opening, said pin having a head arranged in the socket, said pin forming a spring-pressed engagement with the walls of the opening.
5. 4. In a closure for oil chamber openings, the combination of a chamber wall having an opening therein with a socket at its outer end; and a resilient pin in the opening, said pin having a head arranged in the socket, said pin forming a spring-pressed engagement with the walls of the opening, and said head having unequal cross dimensions, the head being of smaller dimensions than the socket to permit of the insertion of a wrench around the head. 15
5. In a closure for oil chamber openings, the combination of a chamber wall having an opening therein with a socket at its outer end; a pin in the opening, said pin having a head arranged in the socket; and a cleaning disc carried by the pin and arranged in the socket. 20

In testimony whereof I have hereunto set my hand.

EDWIN J. ARMSTRONG.
